TABLE PAD

Nelson C. Brewer, Chicago, Ill., assignor to Chas. A. Brewer & Sons, Chicago, Ill., a partnership consisting of Nelson C. Brewer, Kenneth E. Brewer, and Everett R. Brewer

Application February 10, 1933. Serial No. 656,063

3 Claims. (Cl. 45—68.4)

This invention relates to pads of the type commonly used on tables to provide suitable heat insulation against marring the top of the table by heat from a hot receptacle placed on the table. Pads of this type are commonly made in foldable sections so as to occupy but little space when not in use, and they usually comprise a cloth casing and a comparatively thick filler of felt or other fibrous material to provide the heat insulation. In some cases the filler has included one or more sheets of corrugated or indented felted paper designed to produce dead air spaces within the pad, but in such construction continued use of the pad in time flattens the corrugated sheet to such an extent that the spaces which normally form the dead air cells are virtually closed. In other cases it has been proposed to employ a plurality of relatively thick flat sheets each provided with holes, with the two apertured sheets overlapping in such a way that the cells thereof communicate with each other and with holes in the margin of the pad to provide free circulation of air through the pad. This construction, of course, largely defeats the insulating effect of dead air cells.

The chief object of my present invention is to provide an improved table pad of the character described which shall be of simple and inexpensive structure and possess high heat insulating properties which will not diminish with continued use of the pad. With this object in view, the pad of my present invention is characterized by the provision of one or more flat filler sheets each formed with a multiplicity of holes therein that are sealed by flat imperforate sheets on both sides thereof so as to form dead air cells distributed throughout the entire area of the pad.

In structural detail, the invention is capable of considerable modification within its broad principle, but in the accompanying drawing I have illustrated one simple and practical embodiment of the invention which in practice has been found to satisfactorily effectuate the stated purposes and objects thereof, and referring thereto:—

Fig. 1 is a top plan view of the pad unfolded for use, and broken out to show the filler structure.

Fig. 2 is an edge view thereof looking from the bottom of Fig. 1.

Fig. 3 is an enlarged vertical longitudinal section, broken out, on the line 3—3 of Fig. 1.

Fig. 4 is a similar section through one edge of the pad taken on the line 4—4 of Fig. 1.

Fig. 5 is a fragmentary vertical section through

one of the lines of stitches taken, for example, on the line 5—5 of Fig. 1.

Referring to the drawing, I have herein shown the pad as comprising four hinged and foldable sections A, B, C and D, but, of course, the number of sections employed is immaterial and may be varied as desired.

The pad covering preferably comprises, for the top member, a continuous sheet of oil cloth or other water-proof material designated by 10, and for the bottom member a continuous sheet 11 of cloth felt. By reference to Figs. 2 and 3 it will be observed that the four sections are hinged to each other by the simple expedient of providing a pair of depending loops 12 in the top covering member 10, the sides of one loop 12 being cemented to the adjacent edges of the fillers of the sections A and B, and the sides of the other loop 12 being similarly cemented to the adjacent edges of the fillers of the sections C and D. The bottom covering 11 is similarly formed with a central upstanding loop 13, the sides of which are similarly cemented to the adjacent edges of the two intermediate sections B and C. In this way both of the covering members 10 and 11 being flexible, the section A can be folded beneath the section B on a hinge indicated at x in Fig. 3, the section C can then be folded on top of the section B on the hinge indicated at y, and the section D can then be folded on top of the section C on the hinge indicated at z. This construction does not require any stitching at the hinges, although such stitching may be used if desired.

Describing now the preferred filling, which is identical in all of the four sections, 14 designates a comparatively thick sheet of imperforate paper felt which directly underlies the top covering 10, and 15 designates a similar sheet which directly overlies the bottom covering section 11. Between the filler sheets 14 and 15 are interposed a pair of smooth surfaced flat felt sheets 16 and 17, each of which, as best shown in Fig. 1, is formed with a multitude of longitudinal and transverse rows of holes 18 and 19 respectively. Between the perforate sheets 16 and 17 is inserted a comparatively thin imperforate sheet 20, preferably of noncombustible material, such as asbestos, although a sheet of paper, cardboard or other material may be used.

In the formation of the outer edge portions of the pad sections, the top covering 10 is preferably carried down across the edges of the sheets 14 and 16, as shown at 21 in Fig. 4, and then turned inwardly to some extent to form a broad overlap 22 on the edge portion of the central

sheet 20, being cemented to the latter; and the bottom covering 11 is similarly extended up over the edges of the sheets 15 and 17 as shown at 23, and then carried inwardly and cemented to the 5 upper side of the sheet 17 as shown at 24. This forms two composite sections, the upper comprising the parts 10, 14, 16 and 20, and the lower comprising the parts 11, 15 and 17; and these two sections are united around the edges of the 10 pad by inter-locking stitching 25 which, of course, is intermittent on the upper side in the planes of the hinges *x* and *z* and on the lower side in the plane of the hinge *y*.

In the described construction the holes 18 of 15 the flat perforated sheet 16 are sealed at their upper ends by the sheet 14 and at their lower ends by the sheet 20; and similarly the holes 19 of the sheet 17 are sealed at their upper ends by the sheet 20 and at their lower ends by the sheet 20 15. This construction provides throughout the entire intermediate portion of the pad a multitude of dead air cells, which provide a very effective insulation against the transmission of heat from a hot vessel on the pad through the latter to the surface of the table, and thereby safeguards the latter against disfigurement.

I have herein shown and described, for purposes of illustration, one practical and efficient embodiment of the invention, but it is to be understood that the structural details may be varied 25

so long as the principle of sealed dead air cells is preserved, and hence I do not limit the invention to the exact structure shown, but reserve all such variations, modifications and mechanical equivalents as fall within the spirit and purview 80 of the claims.

I claim:

1. A heat insulating table pad, comprising an outer covering, and a filler consisting of a pair of flat imperforate sheets next to said covering, a 85 pair of flat perforated sheets between said imperforate sheets, and a flat imperforate sheet between said perforated sheets.

2. A heat insulating table pad, comprising an outer covering, and a filler therefor consisting of a pair of imperforate felt sheets next to said covering, a pair of flat, smooth surfaced perforated felt sheets between said imperforate sheets, and an imperforate asbestos sheet between said 90 perforated sheets.

3. A heat insulating table pad, comprising an outer covering, and a filler consisting of a pair of flat imperforate felt sheets next to said covering, a pair of flat perforated felt sheets between said imperforate sheets disposed with the perforations of one sheet substantially in register with the perforations of the other, and a flat imperforate asbestos sheet between said perforate sheets. 100
